UNITED STATES PATENT OFFICE.

JOHN M. DUNSMORE, OF THAYER, KANSAS.

PICTURE-PROJECTING APPARATUS.

No. 851,589.

Specification of Letters Patent.

Patented April 23, 1907.

Application filed January 22, 1907. Serial No. 353,582.

To all whom it may concern:

Be it known that I, JOHN M. DUNSMORE, a citizen of the United States, residing at Thayer, in the county of Neosho and State of Kansas, have invented certain new and useful Improvements in Picture-Projecting Apparatus, of which the following is a specification.

This invention has for its object to devise novel means for projecting the picture of a person or object upon a screen and at the same time producing the effect upon a spectator that the sound produced by a person or object emanates from the picture on the screen, said picture being a true representation of the original and giving all the lifelike movements thereof.

The invention contemplates a cabinet of such construction as to suppress or deaden all noise or sound produced therein except such as escapes through a projecting tube which is designed especially for throwing the sound so as to give the impression that the same is produced by the picture appearing upon the screen. The interior of the cabinet is suitably illuminated and mirrors coöperate therewith to throw the picture of the person or object upon the screen placed in front of the cabinet or in such position relative thereto as to receive both the picture and the projected sound.

For a full description of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

45 Figure 1 is a perspective view of an apparatus embodying the invention, a portion of the adjacent or inner side of the cabinet being turned back to disclose the interior. Fig. 2 is a perspective view of the front portion of the cabinet as seen from the interior, the top, bottom and sides being omitted.

The cabinet comprises a suitable framework and sound suppressing inclosing sides, a portion of one of the sides being loose to admit of ingress and egress from the cabinet. The framework 1 is of skeleton formation,

and comprises corner posts, upper and lower longitudinal and transverse beams and suitable stays. The inclosing sides 2 of the cabinet are formed of some sound suppressing material, such as filled textile similar to bed comforts or upholstering. The inclosing sides of the cabinet include the top, bottom, ends and sides, the material being attached to the framework in any suitable way.

60 The cabinet is of a size to receive a person and various objects and contains a lamp 3 or illuminator for lighting the interior of the cabinet and projecting the picture upon a screen through the instrumentality of a lens 4 and mirror 5, the latter being located exterior to the cabinet and about in the plane of the bottom thereof and in such position as to receive the rays of light projected from the object through the lens 4.

65 In the event of the illuminator consisting of a lamp, the hot air and gases are carried off through a tube 6 which is arranged horizontally near the upper portion of the cabinet and set in the side thereof provided with the lens 4. The inner end of the tube 6 flares, as indicated at 7, to collect the sound from within the cabinet and direct the same outward so as to produce the effect upon the spectators of said sound emanating from the 70 picture projected upon the screen 8. It will thus be understood that the tube 6 performs the double function of a vent, as well as a sound conductor, the outward current of hot air and gases also serving to give direction to 75 the escaping sound waves.

80 The screen 8 may be of any construction and size and is arranged in front of the cabinet a suitable distance to receive a clear outline of the image, reflected thereon. The 85 lens 4 is slightly inclined so as to throw the rays of light from the interior of the cabinet upon the mirror 5, the latter in turn reflecting the same upon the screen 8 so as to reproduce thereon the image of the person or object occupying the cabinet.

85 It has been discovered that by having the interior of the cabinet black, and the person or object clad in white, the image or picture appearing upon the screen produces a stereoscopic effect. It is also noted that the image occupies a reverse position from that of the person or object occupying the cabinet. As shown, the person occupying the cabinet appears as playing a violin, the instrument being held in the left hand and the bow in the right. The image projected upon the screen 90

8 is the reverse, that is, it appears as holding the instrument in the right hand and the bow in the left hand. The picture being a representation of the person or object located within the cabinet also presents every movement made, and this feature in connection with that of projecting the sound, results in producing an animated picture, this being heightened should the person sing or speak as the image or picture upon the screen will likewise follow all the facial movements incident to singing.

A mirror 8^a is located in the front portion of the cabinet just below the illuminator 3, the purpose being to cut off direct rays of light and insure a sharp outline of the image or picture reflected upon the screen.

Having thus described the invention, what is claimed as new is:

- 20 1. A picture projecting apparatus comprising a cabinet adapted to receive the person, object or thing whose picture is to be reproduced, an illuminator arranged within the cabinet, a light ray projecting lens fitted to the lower portion of the said cabinet and inclined to the perpendicular, an approximately horizontal mirror arranged below the lens for reflecting the image, and a screen exterior to the lens for receiving the picture.

2. In a picture projecting apparatus comprising a cabinet, an illuminator located in the upper forward portion of the cabinet, an inclined mirror located immediately below the illuminator to cut off direct rays of light and insure a sharp outline of the picture, an inclined lens fitted in the lower portion of the front of the cabinet below the said mirror, an approximately horizontal mirror exterior to the cabinet and below the said lens, and a screen exterior to the cabinet for receiving the reflected image.

3. In apparatus of the character specified, the combination of a cabinet, a lamp arranged within the cabinet for lighting the interior thereof, means for projecting the image of a person or object from the cabinet upon a screen, a tube arranged to carry off the hot air and gases from the said lamp and also serving to project any sound produced within the cabinet, and a screen exterior to the cabinet for receiving the reflected image and the projected sound.

In testimony whereof I affix my signature in presence of two witnesses.

JOHN M. DUNSMORE.
